United States Patent Office

Des. 225,933
Patented Jan. 16, 1973

225,933

CHAIR

Gordon L. Duern and Donald S. Griffin, Kitchener,
Ontario, Canada, assignors to Electrohome Limited,
Kitchener, Ontario, Canada

Filed Mar. 23, 1971, Ser. No. 127,444

Term of patent 14 years

Int. Cl. D6—02

U.S. Cl. D6—69

FIG. 1

FIG. 2

FIG. 1 is a perspective view of a chair showing our design, taken from the front and to one side, looking down obliquely; and

FIG. 2 is a perspective view of the chair of FIG. 1, taken from the rear and to one side looking down obliquely, showing the portion not visible in FIG. 1.

We claim:

The ornamental design for a chair, as shown.
